UNITED STATES PATENT OFFICE.

GEORGE E. SANFORD, OF CHICAGO, ILLINOIS, ASSIGNOR, BY MESNE ASSIGNMENTS, TO SANFORD CLARIFYING AND SEPARATING COMPANY, A CORPORATION OF DELAWARE.

LIQUID-SEPARATOR.

1,016,366.

Specification of Letters Patent.

Patented Feb. 6, 1912.

Application filed July 27, 1909. Serial No. 509,927.

To all whom it may concern:

Be it known that I, GEORGE E. SANFORD, a citizen of the United States, residing at Chicago, in the county of Cook and State of Illinois, have invented certain new and useful Improvements in Liquid-Separators, of which the following is a specification.

This invention relates to that class of centrifugal machines known in the art as "liquid-separators" which are adapted to separate whole or fresh milk, sugar liquids, fruit juices, sugar or syrup from sugar beet, sorghum plant, maple sap or the like, which liquids are to be separated into constituent parts of different specific gravities; and the invention consists of the parts and constructions and combinations of the parts herein-after fully described, illustrated in the accompanying drawings and particularly 20 pointed out in the appended claims.

Impurities in liquids are now commonly removed by filtering, precipitating, decanting and skimming. In the present instance, the impurities are removed from the liquid 25 by running the liquid through a rapidly revolving drum wherein the centrifugal force generated by the motion of the drum, acting in unison with the forces of the different specific gravities of the substances in the 30 liquid and the liquid itself will force those having a greater specific gravity than the liquid to gravitate toward and be deposited at the periphery of the drum where they will be retained by disks, and those having a 35 lighter specific gravity than the liquid will gravitate and be deposited at the axis and be retained by disks, the clarified liquid being drawn off through an opening midway between the periphery and the axis.

40 The drum is so arranged that when the spaces between the disks are filled with impurities the drum can be cleansed by flushing and the impurities washed out, or the disks can be withdrawn and cleaned, if desired.

In the accompanying drawings forming 50 part of this specification, and in which similar characters of reference denote corresponding parts—Figure 1 is a vertical sectional view of the invention in operative condition indicating the separation of the liquids of different specific gravities. Fig. 2 is a similar view illustrating the invention with its parts assembled for the flushing

cleansing operation. Fig. 3 is a horizontal 55 sectional view. Fig. 4 is a top plan view.

Referring now more particularly to the accompanying drawings, the reference character 1 indicates a drum mounted for rotation upon the central shaft 2 which is 60 mounted at its lower end in the bearing 3 and at its upper end through a supporting part 4, the said shaft being provided with a longitudinal bore 5 extending substantially throughout its entire length and at its upper 65 end provided with a funnel 6 which has communication with said bore 5 for a purpose presently explained, the said central shaft also having sets of openings 7 leading from its bore to the interior of an internal 70 drum 8 mounted within the outer drum 1 and rotatable with the latter upon said shaft 2.

The drums are arranged so that they may 75 rotate with the shaft 2 when the latter is driven through any suitable power (not shown), and which may have connection with the drive pulley 9 secured to the upper end of the shaft 2, as shown.

Two sets of shelves 10 and 11 are 80 removably and slidably secured to the inner surface or walls of the outer and inner drums 1 and 8, respectively, and preferably in alinement. These shelves 10 and 11 may be secured in position by connection with the inner walls of the drums, but are preferably supported loosely against the drums by the uprights 12 and 13, respectively, which are provided with a plurality of notches 14 and 15, respectively, for the reception of the 85 corresponding edges of said shelves. These shelves 10 and 11 are adapted to retain the heavier impurities, as shown in heavy lines in Fig. 1.

Likewise disposed against the outer surface of the inner drum 8 is a plurality of shelves 16 which are further supported by the uprights 17 provided with notches 18 to receive the outer edges of said shelves, the character 19 indicating another plurality of 100 shelves which are secured to the shaft 2 with their peripheries fitted in the notches 20 of the upright supporting elements 21. The plurality of shelves 16 and 19 retain the lighter impurities, as shown by the 105 heavy lines in Fig. 1.

The liquid to be clarified is let into the inner drum 8 by means of a valved inlet 22

through an opening 23 disposed at the top of the inner drum and centrally thereof, the incoming liquid falling upon the shelf 19 disposed above the central vertically alining shelves 19, passes between the shelves 11 and 19, there being sets of shelves 24 disposed immediately beneath the openings or passages between the shelves 11 and 19 so as to arrest the flow of liquid and separate the current to assist in separating the impurities as the liquid passes downwardly toward the bottom of the inner drum. As shown, the inner drum is spaced at its lower end from the bottom of the outer drum so that the liquid may finally pass upwardly in the machine between the inner and outer drums, as indicated by arrows in the accompanying drawings, there being shelves 25 secured to the lower edge of the inner drum 8, which are wider than the before-mentioned shelves, adapted to hold back the liquid and force it between both sets of shelves 11 and 19 until the spaces between the latter disks are full of liquid. The separating shelves 24 divide the current, giving the impurities an initial start in the direction in which the united forces of the specific gravities and the centrifugal force is drawing them, the bodies of the liquid between the shelves being nearly at rest and the combined forces acting on them with the result that the heavier impurities are deposited between the shelves 11 and the lighter impurities deposited between the shelves 19. The liquid finally passes under the shelves 25 at the bottom of the inner drum and flows upwardly between the shelves 10 and 16 arranged between the inner and outer drums and at the top of the space between the inner and outer drums into liquid is held back by the top of the outer drum until the spaces between the shelves 10 and 16 are full and the same action has taken place as in the inner drum, the remaining impurities being deposited between the two sets of shelves 10 and 16, the clarified liquid flowing out through the outlets 26 at the top of the drum and which outlets are formed between the two removable closures 27 and 28.

When the spaces between the shelves become filled with impurities, the drum can be cleaned by removing the sectional covers 27 and 28 and subsequently removing the shelves and their supporting upright elements; or if preferred, the machine may be cleaned or cleansed without removing the various parts thereof. In order to cleanse the machine without removing the various parts, I provide the outer and inner drums 1 and 8, respectively, with vertical offsets 29 and 30, respectively, each of which is provided with a vertical bore 31 and 32, respectively, communicating with which bores are the apertures 33 and 34, respectively.

Fitted in the bores 31 and 32 are the valve

rods 35 and 36, respectively, each having apertures 37 adapted to be thrown into and out of alinement with the apertures 33 and 34 of the drums, they being out of alinement with the perforations of the latter during the clarifying operation, and in alinement therewith when it is desired to flush the drums. Thus by shutting off the valved inlet 22 and turning on the valved inlet 37' from any suitable water source, water may be let into the bore 5 of the shaft 2, which will pass outwardly through the openings 7 in the shaft and gradually work from the bottom upwardly in the outer and inner drums 1 and 8, respectively, incident to the centrifugal action of the drums passing through the apertures 34 of the inner drum and also through the apertures 33 in the outer drum, the valve rods 35 and 36 being turned so that their openings 37 may aline with the apertures 33 and 34 prior to turning on the valved water inlet 37'. In this way, the machine may be thoroughly flushed and after flushing, the valve rods 35 and 36 are turned so that their openings 37 will be out of alinement with the apertures 33 and 34 of the outer and inner drums, respectively, when the machine will be ready to resume the clarifying operation.

Any suitable means may be employed for operating the valve rods 35 and 36, but, as shown, the valve rods 36 extend through the top of the machine and are provided with the oppositely disposed projections 38 and 39 (see Fig. 4). These projections 38 and 39 are so arranged that during the clarifying operation they will not engage the links 40 and 41 pivoted at 42 to the pivot block 43 and at 44 and 45, respectively, to the lever 46, the said projections 38 and 39 passing between said links 40 and 41 during the clarifying operation. When it is desired to flush the machine, the lever 46 is forced inwardly, causing the link 40 to engage the projection 38 on each valve rod 36 and turn the latter so that its openings 37 may aline with the openings 34 of the inner drum to permit of the passage of water therethrough. In the same way, the valve rods 35 of the outer drum 1 may be manipulated by the lever 47 of the same form, construction and arrangement as the lever 46, including the parts associated therewith, the only difference being that the valve rods 35 are extending upwardly into the outer drum, while the valve rods 36 of the inner drum are extended downwardly. To resume the clarifying operation after the flushing of the machine, the levers 46 and 47 are pulled outwardly, which causes their links 41 to engage the projections 39 of the valve rods and turn the latter to close the openings 33 and 34 of the outer and inner drums, respectively, so that the clarifying of the liquid may be continued. It will thus be

understood that the valve rods of the inner and outer drums may be manipulated while the drums are rotating.

The notches in the uprights which support the shelves may obviously be disposed at various distances apart so that the shelves may be arranged adjustably within the drums. In other words, more notches than are shown in the uprights may be employed, as is obvious, to receive the shelves, so that they may have adjustment with relation to one another or together, within the drums. In any event, the shelves may be readily removed from the drum when desired, as has been already stated.

What is claimed is:—

1. In a centrifugal separator, an inner and an outer drum, sets of shelves between the inner and outer drums, sets of shelves within the inner drum, and means whereby the drums may be rotated, the shelves within the inner drum and the shelves between the inner and outer drums being arranged to effect a deposit of the heavier impurities at the peripheries of the drums and the lighter impurities at the axis thereof and permit of the escape of the clarified liquid from between said deposited impurities.
2. In a centrifugal separator, an inner and an outer drum, the drums being mounted to rotate together, shelves between the inner and outer drums, and shelves within the inner drum, the shelves being arranged whereby upon rotation of the drums the impurities will be deposited and retained between the shelves and the clarified liquid permitted to escape from the drums.
3. In a centrifugal machine, an inner and an outer drum, the drums being mounted for rotation, two sets of shelves arranged between the drums and two sets of shelves arranged within the inner drum, one set of shelves in the space between the drums and one set of shelves in the inner drum being adapted to retain the heavier impurities of the liquid and the other set of shelves between the drums and within the inner drum being adapted to retain the lighter impurities of the liquid.
4. In a centrifugal machine, a rotatable drum, two sets of shelves in the drum, one set of shelves arranged to retain the heavier impurities of the liquid and the other set of shelves being arranged to retain the lighter impurities of the liquid during rotation of the drum, and another set of shelves cooperating with the aforesaid shelves to retard and divide the flow of liquid between said other sets of shelves.
5. In a centrifugal separator, an inner and an outer drum, the drums being mounted for rotation together, two sets of shelves arranged between the drums, two sets of shelves arranged within the inner drum, one set of shelves in the space between the drums

being arranged to retain the heavier impurities, and the other sets of shelves between the drums being arranged to retain the lighter impurities, one set of shelves in the inner drum being adapted to retain the heavier impurities and one set therein being adapted to retain the lighter impurities, and a set of shelves coöperating with each of the aforesaid two sets of shelves to arrest and divide the current to give the impurities in the liquid an initial movement in the direction in which they are to be deposited.

6. In a centrifugal separator, a rotatable inner drum and a rotatable outer drum, spaced apart, shelves arranged in the space between the drums, and shelves arranged within the inner drum so that the liquid may pass over the shelves of the inner drum and upwardly in the space between the drums and be acted upon by the shelves in its passage through the inner drum and upwardly through the space between the drums to separate the heavier and lighter impurities from each other and from the liquid and deposit the impurities upon opposite sides of the liquid, thereby separating the liquid in its passage through the inner drum and upwardly between the drums incident to the centrifugal force generated by rotation of the drums and the contact of the liquid with the disks and permitting the escape of the clarified liquid from between the deposited bodies of impurities.

7. In a centrifugal separator, a rotatable inner drum and a rotatable outer drum spaced apart, shelves arranged in the space between the drums, shelves arranged within the inner drum, the inner drum terminating short of the bottom of the outer drum so that the liquid may pass over the shelves of the inner drum and upwardly in the space between the drums and be acted upon by the shelves in its passage through the inner drum and upwardly through the space between the drums to separate the heavier and lighter impurities from each other and from the liquid and deposit the impurities upon opposite sides of the liquid, thereby separating the liquid in its passage through the inner drum and upwardly between the drums incident to the centrifugal force generated by rotation of the drums and the contact of the liquid with the shelves and permitting the escape of the clarified liquid from between the deposited bodies of impurities.

8. In a centrifugal separator, a rotatable inner drum and a rotatable outer drum spaced apart, shelves arranged in the space between the drums, shelves arranged within the inner drum, the inner drum terminating

short of the bottom of the outer drum so that the liquid may pass over the shelves of the inner drum and upwardly in the space between the drums and be acted upon by the shelves in its passage through the inner drum and upwardly through the space between the drums, thereby separating the liquid in its passage through the inner drum and upwardly between the drums incident to the centrifugal force generated by rotation of the drums and the contact of the liquid with the shelves, shelves arranged to hold back the flow of liquid temporarily in its passage from the inner drum to the space between the drums, and other shelves arranged for coöperation with the first mentioned disks within the inner drum and in the space between the drums to arrest and divide the liquid, thereby giving the liquid an initial movement in the direction in which they are drawn.

9. In a centrifugal separator, the combination with an inner and an outer drum spaced apart, means whereby the drums may be rotated, the inner drum having an inlet to receive the liquid and the outer drum having an outlet to discharge the clarified liquid, shelves within the inner drum and shelves between the drums, other shelves arranged to retard and divide the liquid in the inner drum prior to its passage to the space between the drums, and the discharge outlet of the outer drum being arranged to retard movement of the liquid to force the liquid between the shelves whereby the impurities may be deposited and retained between the shelves.

10. In a centrifugal separator, an inner drum and an outer drum spaced apart, means whereby the drums may be rotated, shelves in the inner drum, and shelves between the drums, the shelves being constructed and arranged to permit the clarified liquid to be thrown off while the impurities are held between the shelves.

11. In a centrifugal separator, the combination with an outer drum provided with openings in its walls, valve rods disposed in the walls of the outer drum for coöperation with said valve openings, means whereby the valve rods may be operated to open and close said valve openings, a second drum disposed within the outer drum with its side walls in spaced relation thereto and with its side walls provided with valve openings, valve rods mounted in the walls of the inner drum for coöperation with the valve openings thereof, means whereby the valve rods may be operated to open and close the valve openings of the inner drum, disks disposed within the inner drum, shelves disposed in the space between the inner and outer drums, and means whereby the drums may be rotated.

12. In a centrifugal separator, a hollow

shaft, having openings communicating with the hollow of the shaft, an outer drum provided with valve openings in its side walls, valve rods fitted in the side walls of the outer drum for coöperation with the valve openings thereof, said outer drum being rotatable with said shaft, means whereby the shaft may be rotated, an inner drum disposed within the outer drum with its side walls in spaced relation to the side walls of the outer drum and whose side walls are provided with a plurality of valve openings, valve rods disposed in the walls of the inner drum for coöperation with the valve openings of the inner drum, means whereby the valve rods of the inner drum may be operated to open and close the valve openings of the inner drum, means to convey water to the hollow shaft, shelves in the inner drum, and shelves in the space between the drums.

13. In a centrifugal separator, a rotatable drum whose axis is arranged centrally thereof, a second drum within the first mentioned drum and disposed in spaced relation thereto, sets of shelves in the inner drum, one set being arranged at the periphery thereof and the other set at the axis thereof, shelves in the outer drum, the shelves in the outer drum being constructed and arranged one set at the periphery thereof and the other set in spaced relation to the periphery set of shelves, means for rotating the drums together, and upon rotation of the drums the shelves effecting a deposit of the heavier impurities at the peripheries and the other shelves effecting a deposit of the lighter impurities and permitting escape of the clarified liquid from between the bodies of deposited impurities.

14. In a centrifugal separator, two concentric drums, means for rotating the drums, and means at the peripheries of the drums within the same adapted to effect a deposit of and to retain the heavier impurities separated by rotation of said drums.

15. In a centrifugal separator, a drum, a second drum within the first mentioned drum, means for rotating the drums, means for passing liquids through one drum and subsequently through the second drum, and means placed within said drums for retaining the impurities separated from said liquids by the centrifugal force through the rotation of the drums, and permitting the escape of the clarified liquid while the impurities are retained within the drum.

16. A centrifugal separator comprising a drum, a second drum within the first mentioned drum, an inlet to the first mentioned drum, an outlet from the second named drum, a passage between the drums, means for retarding liquid passing through said drums, means for rotating the drums, and means for retaining impurities at both the periphery and axis of each of said drums

and permitting the escape of the clarified liquid.

17. A centrifugal separator comprising a drum adapted for rotation, a second drum within the first mentioned drum concentric therewith and adapted for rotation thereby, an inlet to said first mentioned drum, an outlet from the second mentioned drum, a passage between the drums, means for retarding the flow of liquids through the drums, means for rotating the drums, means for retaining the heavier impurities thrown to the peripheries of the drums in rotation, and means for retaining the lighter impurities at the axis of the drum.

18. A centrifugal separator comprising a drum, means for conveying liquids to the drum, means for retarding the flow of liquids through the drum, means to retain the heavier impurities thrown to the periphery of the drum by rotation thereof, and means for retaining the lighter impurities drawn to the center of the drum by rotation thereof, the two last mentioned means being disposed directly opposite each other.

19. In a centrifugal machine, a rotatable drum means constructed and arranged within the drum to retain the heavier impurities of the liquid, means constructed and arranged in the drum to retain the lighter impurities of the liquid, and means constructed and arranged to coöperate with both of the aforesaid means to retard and divide the flow of the liquid into coöperative relation with both of the first mentioned means.

20. In a centrifugal machine, an inner and an outer rotatable drum, the bottom of the inner drum being spaced from the bottom of the outer drum to establish communication between the drums, means constructed and arranged to convey the liquid to the inner drum, the liquid passing downwardly through the inner drum and upwardly through the outer drum and discharged from the latter, and means constructed and arranged within the drums to retain the heavier and lighter impurities in spaced bodies and permit the liquid to flow through the drums between the spaced bodies of impurities and discharged while said impurities are held in rest within the drums.

21. In a centrifugal separator, a rotatable drum and sets of shelves disposed within the drum, one set of shelves being oppo-

site to another set of shelves and arranged within the drum with one set of shelves at the periphery and the other set at the axis, whereby the centrifugal force generated by the revolving drum will effect a deposit of the heavier impurities at the periphery of the drum and a deposit of the lighter impurities at the axis of the drum and permit the escape of the clarified liquid from between said impurities.

22. In a centrifugal separator, a rotatable drum and sets of shelves disposed within the drum and arranged to provide spaces at the periphery and also at the axis of the drum with a vertical passage between the opposite spaces whereby the centrifugal force generated by the revolving drum will effect a deposit of the heavier impurities in the spaces at the periphery of the drum and a deposit of the lighter impurities in the spaces at the axis of the drum out of the path of the current of the clarified liquid and permit the escape of the clarified liquid from between said impurities.

23. In a centrifugal separator, a rotatable drum and sets of shelves disposed within the drum, the shelves being arranged whereby the centrifugal force generated by the revolving drum will effect a deposit of heavier impurities at the periphery of the drum and a deposit of the lighter impurities at the axis thereof and permit the escape of the clarified liquid from the space between said deposited impurities, whereby the deposited impurities are not subjected to the strong current of the clarified liquid which passes through the space between the deposited impurities.

24. A centrifugal liquid clarifier comprising a drum having a single discharge opening at its top, means for rotating the drum, and means constructed and arranged at the axis and also at the periphery of the drum to retain impurities deposited at the periphery and at the axis of the drum and arranged to protect the deposited impurities from the action of the clarified liquid which escapes only through said single discharge opening from between said impurities.

In testimony whereof I affix my signature in presence of two witnesses.

GEORGE E. SANFORD.
